UNITED STATES PATENT OFFICE.

LEWIS C. MARR, OF WALL ROSE, PENNSYLVANIA.

STEP FOR VEHICLES, &c.

No. 868,352.

Specification of Letters Patent.

Patented Oct. 15, 1907.

Application filed February 16, 1907. Serial No. 357,675.

To all whom it may concern:

Be it known that I, LEWIS C. MARR, a resident of Wall Rose, in the county of Beaver and State of Pennsylvania, have invented a new and useful Improvement in Steps for Vehicles, &c.; and I do hereby declare the following to be a full, clear, and exact description thereof.

My invention relates to steps and has special reference to the class of steps that are used on vehicles, such as ice, laundry, and other wagons.

The object of my invention is to provide a cheap simple and efficient form of a step which can be folded up when not in use, can be locked when in use, and will also permit its swinging when in its lowered position to prevent injury thereto.

My invention consists, generally stated, in the novel arrangement, construction and combination of parts, as hereinafter more specifically set forth and described and particularly pointed out in the claims.

To enable others skilled in the art to which my invention appertains to construct and use my improved step, I will describe the same more fully, referring to the accompanying drawing, in which—

Figure 1 is a rear view of a wagon showing my improved step applied thereto and in its folded position. Fig. 2 is a side view of the rear end of the wagon showing the step in use. Fig. 3 is a side view of the step showing the same in another position. Fig. 4 is a like view of the same in its folded position. Fig. 5 is a perspective view of the step support.

Like symbols of reference herein indicate like parts in each of the figures of the drawing.

As illustrated in said drawing, A represents a vehicle, such as a wagon, which has the usual bed a thereon and to the bottom b of said bed my improved step is supported. This step consists of the brackets 2 which are secured at their upper ends by bolts 3 to a sill or bar c extending across the under face of the wagon bottom b and their lower ends carry the cross-bar 4 between inwardly extending portions 2' on the same. The bar 4 extends beyond the brackets 2 and a bracing bar 5 fits around each end of the same and is bolted on its upper end to another sill or bar d extending across the under face of the wagon bottom b in the rear of the sill c, while the ends of the cross-bar 4 are provided with the nuts 6 engaging with the same and bearing against the bracing-bars 5.

A collar 7 is formed on the cross-bar 4 adjacent to each of the brackets 2 and between said collars and said brackets the supporting arms 8 for carrying the step-plate 9 of the step member or portion 1 are placed. These arms 8 are revoluble upon the cross-bar 4 by means of a slot 10 through which the said bar passes, and secured above the ends of said arms and between the same is the cross-rod 11. A spiral spring 12 is con-

nected at one end to the center of said rod 11 and its opposite end is connected to the under face of the wagon bottom b. The step-plate 9 extends across and between the arms 8 and is connected to extending portions 13 on said arms by means of the bolts 14.

60

The use and operation of my improved vehicle step is as follows—As shown in Fig. 1 and Fig. 4 the step-portion 1 is in its folded position and is locked and held from moving outward by means of a projection 15 formed on one of the brackets 2 and extending below the bar 4, which is adapted to engage with one of the lugs or extensions 16 formed on the end of one of the arms 8 adjacent to the rod 11. The step-portion 1 when in this position is held from moving backward by means of the side or end edge of the step-plate 9 70 engaging with bars, or by means of the spring 12 connected to the bottom b and the said portion through the rod 11 being extended, according to the length desired of the step-plate 9.

When it is desired to use the step-portion 1, it is 75 pressed or pulled down in a vertical line, which will allow the arms 8 and plate 9 to be lowered down through the bar 4 moving in the slots 10 in said arms and thereby freeing the lug 16 on said arms from the projection 15 on the brackets 2, so that said step-portion 80 can be thrown outward on the bar 4 through the slots 10 in said arms 8 and by the extension of the spring 12 being released. When the step-portion 1 is thus thrown out it will assume the position shown in full lines in Fig. 3 and upon being used by a person, as 85 shown in Fig. 2 the said step portion will be brought down to a substantially vertical position. When the step portion 1 is so lowered the bar 4 will move along the slots 10 in the arms 8 of said portion 1 during the lowering of said arms and the spring 12 connecting 90 said arms and bottom b will be extended, while such portion will be prevented from rotating and held in such position by means of the lugs 16 on said arms engaging with the inwardly extending portions 2' on the brackets 2 while so being used.

95

When the step-portion 1 is not in use, the said portion will be raised on the bar 4 through the slots 10 in the arms 8 by reason of the extension of the spring 12 being released, so that portion will again assume the position shown in full lines Fig. 3. While in this position the said portion 1 will be enabled to swing backwards and forwards through the medium of said spring 12 in case of any obstacle coming against said portion 1 during the backing of wagon, or from any other causes, so that when in this position and free, the step-portion 100 is always ready for use. When the step-portion 1 is in this position and it is desired to raise the same to its folding position, it is turned forward by its slotted arms 8 on the bar 4 to a vertical position and pressed downward so that the lug 16 on the arm 8 is below the pro- 110

jection 15 on the bracket 2, and upon pressure being released, the said spring 12 will raise the said portion to its folded position and allow the said lug to engage the said projection for locking and holding said portion 5 in such folded position.

It will be evident that my improved vehicle step can be applied to any sort of vehicle and of any kind, while such step can be also applied and used on other objects and for other purposes, and that various modifications 10 and changes in the design, construction and operation of the same may be resorted to without departing from the spirit of the invention or sacrificing any of its advantages. It will also be obvious that my improved step when in its folded position will not interfere with 15 or be in the way of the use of the wagon or other object upon which it is used, and it can be easily and quickly folded or set in position for use when desired. The device is strong and durable and will not get out of order, and when folded up or in position for use will 20 not be liable to become broken or injured. It will also form a rigid and strong device when in use and will be securely held and locked in either its folded or operative position until it is desired to move the same to the other position desired.

25 What I claim as my invention and desire to secure by Letters Patent is—

1. In a step, the combination of stationary supporting brackets, swinging arms carrying the step pivotally mounted on and between said brackets through slotted connections, and lugs on said arms engaging with said brackets 30 to lock the step in the lowered position and prevent the same from rotating.

2. In a step, the combination of stationary supporting brackets, swinging arms carrying the step pivotally mounted on and between said brackets through slotted connections, and lugs on said arms and engaging with a stationary projection for locking the arms and step in the 35 folded position.

3. In a step, the combination of stationary supporting 40 brackets, and a spring controlled swinging step pivotally mounted on and between said brackets through slotted connections.

4. In a step, the combination of stationary supporting brackets, and spring controlled swinging arms carrying the step pivotally mounted on and between said brackets 45 through slotted connections.

5. In a step, the combination of stationary supporting brackets, and spring controlled swinging arms carrying the step pivotally mounted on and between the said brackets through slots in said arms. 50

6. In a step, the combination of stationary supporting brackets having a bar between the same, and spring controlled swinging arms carrying the step pivotally mounted on the said bar and between said brackets through slots in said arms. 55

7. In a step, the combination of stationary supporting brackets, and spring controlled swinging arms carrying the step pivotally mounted on and between said brackets through slotted connections, and means on said arms for holding the step in the lowered position and preventing the 60 same from rotating.

8. In a step, the combination of stationary supporting brackets, spring controlled swinging arms carrying the step pivotally mounted on and between said brackets through slotted connections, and means on said arms 65 and engaging with said brackets to lock the step in the lowered position and prevent the same from rotating.

9. In a step, the combination of stationary supporting brackets, spring controlled swinging arms carrying the step pivotally mounted on and between said brackets 70 through slotted connections, and lugs on said arms engaging with said brackets to lock the step in the lowered position and prevent the same from rotating.

10. In a step, the combination of stationary supporting brackets, spring controlled swinging arms carrying the 75 step pivotally mounted on and between said brackets through slotted connections, and means on said arms for locking the arms and step in the folded position.

11. In a step, the combination of stationary supporting brackets, spring controlled swinging arms carrying the 80 step pivotally mounted on and between said brackets through slotted connections, and lugs on said arms and engaging with a stationary projection for locking the arms and step in the folded position.

In testimony whereof, I the said LEWIS C. MARR have 85 hereunto set my hand.

LEWIS C. MARR.
